UNITED STATES PATENT OFFICE.

WILLIAM N. MARSDEN, OF AMSTERDAM, NEW YORK, ASSIGNOR TO FOWNES BROTHERS & CO., A COPARTNERSHIP OF LONDON, ENGLAND, CONSISTING OF WILLIAM GARDINER RIGDEN, HENRY URWICK, W. FOWNES RIGDEN, E. FOWNES RIGDEN, S. FOWNES RIGDEN, AND LESLIE ALAN SPALL.

CAM-FOLLOWER MECHANISM.

1,299,754.

Specification of Letters Patent. Patented Apr. 8, 1919.

Application filed October 24, 1918. Serial No. 259,574.

To all whom it may concern:

Be it known that I, WILLIAM N. MARSDEN, a citizen of the United States, residing at Amsterdam, county of Montgomery, and State of New York, have invented certain new and useful Improvements in Cam-Follower Mechanisms, of which the following is a specification.

Reference may be had to the accompanying drawings, and the reference characters marked thereon, which form a part of this specification. Similar characters refer to similar parts in the several figures therein.

This invention relates to cam-follower mechanism engageable with teeth or steps on the periphery of a cam-wheel which teeth or steps are of substantially the same angular extent measured circumferentially of the wheel while the respective steps are at different distances from the center of the wheel.

The principal object of the invention is to produce a substantially uniform throw of the cam-follower-actuated-mechanism by the successive teeth or steps of the cam-wheel.

Other objects will appear in connection with the following description.

The invention is particularly adapted for the cam-follower-mechanism of a flat warp knitting machine such as is used in making cloth for the manufacture of gloves.

Figure 1 of the drawings is a view in side elevation showing my improved cam-follower-mechanism.

Fig. 2 is a vertical cross-section of the same taken on the broken line 2-2 in Fig. 1.

Fig. 3 is a horizontal section through the cam-follower-roller and the slideway for the member which carries the roller taken on the broken line 3-3 in Fig. 1.

Referring to the drawings wherein the invention is shown in preferred form, 1 is a cam-wheel, rotatively mounted on a frame, 2, of a machine to which my invention is to be applied, and 3 is a cam-follower-actuated member in the form of a bell-crank lever fulcrummed at 4, upon the frame of the machine.

In the application of the invention to a

fast warp knitting machine, the lever, 3, is connected at 5, with one of the guide-bars of the machine; but as the construction and manner of operation of such a fast warp knitting machine is well understood in the art, and the general construction of such machine forms no part of my invention, the details thereof are not herein shown or described.

The cam-wheel, 1, has on its periphery a series of teeth or steps, 1^a, of substantially the same angular extent measured circumferentially of the wheel, while the respective steps are at different distances from the center of the wheel.

A step-by-step rotative movement may be imparted to the cam-wheel, 1, in the usual or any known manner whereby its steps or teeth, 1^a, are successively brought into engagement with a cam-follower, 6, carried by the lever, 3.

In the preferred form of my invention, the cam-follower, 6, is in the form of a roller rotatively mounted in the lower end of an arm, 7, pendulously carried by the lower horizontal arm of the lever, 3.

The arm, 7, which forms a housing for the roller, 6, has its lower end laterally offset to form trunnion members, 8, which closely fit and are adapted to slidably reciprocate in openings in a slideway-frame, 9, in fixed relation to the main frame, 2, of the machine.

The slideway, 9, extends in a direction radial to the cam-wheel, 1, and is so located with respect to the successive idle positions of the cam-wheel that at each idle position thereof the cam-follower, 6, will engage one of the teeth or steps, 1^a, at substantially the middle of the tooth or step.

The cam-follower, 6, thus engages the successive teeth or steps on the periphery of the cam-wheel, 1, always at the same point which is in a straight line passing from the center of the cam-wheel to the center or the contacting point of the cam-follower, 6.

The movement imparted to the cam-follower is thus determined entirely by the distances from the center of the cam-wheel, 1,

of the successive steps or teeth, 1^a, and is not influenced by the particular angular position of the lever, 3, which varies from time to time as the teeth, 1^a, are nearer to 5 or farther from the center of the cam-wheel.

The pendulous connection, 7, between the cam-follower and the lever, 3, reduces to a negligible quantity any difference in the throw imparted by the cam-follower to the 10 lever, 3, due to different angular positions of the lever, 3.

I have described my invention in its application to a single cam-wheel.

In fast warp knitting machines, two or 15 more cam-wheels are employed, and I have shown in the drawings my invention applied to two such cam-wheels fixed upon the same shaft, 10, but as each of the cam-follower-mechanisms is a duplicate of the other, 20 further description of the same is unnecessary.

In the drawings one of the cam-follower-rollers is shown engaging a step or tooth on 25 one of the cam-wheels at a substantially different distance from the axis of the cam-wheels than the tooth or step on the other

cam-wheel which is engaged by the other cam-follower-roller.

What I claim as new and desire to secure by Letters Patent is—

In a device of the class described and in combination, a frame; a cam rotatively mounted upon the frame and having peripherally disposed steps or teeth at different distances from its axis of rotation, said 30 steps or teeth being of equal angular extent measured circumferentially of the cam; a slideway in fixed relation to said frame extending in a direction radial to said cam; a cam-follower-roller engageable with the successive steps or teeth on said cam; an arm carrying said cam-follower-roller, said arm having on its inner end a trunnion concentric with said roller movable rockably and longitudinally in said slideway; and a member having a pivotal connection with the outer end of said arm, whereby said member is actuated by said cam.

In testimony whereof, I have hereunto set my hand this 16th day of October 1918.

WM. N. MARSDEN.
